WASHING MACHINE AGITATOR

Robert S. Trembath, Benton Harbor, Mich., assignor to
Whirlpool Corporation, a corporation of Delaware

Filed May 29, 1967, Ser. No. 7,304

Term of patent 14 years

(Cl. D49—1)

FIGURE 1 is a perspective view of a washing machine agitator embodying my new design;

FIGURE 2 is a front elevational view thereof;

FIGURE 3 is a top plan view thereof with the post portion removed and as indicated by the lines 3-3 of FIGURE 2;

FIGURE 4 is a perspective view of a modified arrangement of the washing machine agitator, showing the vanes in an extended position.

FIGURE 5 is a front elevational view thereof; and

FIGURE 6 is a top plan view thereof with the post portion removed and as indicated by the lines 6-6 of FIGURE 5.

The dominant features of my design reside in the portions shown in full lines.

Portions are broken away in FIGURES 2 and 5 for convenience of illustration.

I claim:

The ornamental design for a washing machine agitator, as shown and described.
